UNITED STATES PATENT OFFICE.

WILLIAM McCORMICK NEALE, OF GREENSBORO, NORTH CAROLINA.

SHADE-FIXTURE.

1,347,966.

Specification of Letters Patent.

Patented July 27, 1920.

Application filed August 14, 1919. Serial No. 317,528.

To all whom it may concern:

Be it known that I, WILLIAM McC. NEALE, a citizen of the United States, and a resident of Greensboro, in the county of Guilford and State of North Carolina, have invented certain new and useful Improvements in Shade-Fixtures, of which the following is a specification.

My invention is an improvement in shade fixtures, and has for its object to provide a simple, efficient, inexpensive device of the character specified for permitting a shade to be raised or lowered when desired, without the necessity of springs, and without the necessity of handling the shade itself.

In the drawings:

Figure 1 is an end view of a shade having the fixture;

Fig. 2 is a front view of one end of the shade;

Fig. 3 is a side view, with parts in section, showing a modified form of supporting bracket;

Fig. 4 is an end view;

Figs. 5 and 6 are views similar to Figs. 3 and 4, showing another embodiment;

Figs. 7 and 8 are views similar to Figs. 3 and 4, showing another embodiment.

In Figs. 1 and 2 the invention is shown in connection with a shade 1 of ordinary construction, having at one end the stiffening bar 2 held in a loop 3 in the shade, and connected at the other end to a roller 4. At one end this roller has the usual trunnion supported by the usual bracket. At the other the roller has a trunnion, upon which is mounted a reel 5, the reel being secured to the trunnion in any suitable manner, as, for instance, by flattening the trunnion and the hub opening of the reel. Upon this reel winds a cord 6, the said cord being rigidly secured at one end to the reel and the cord is so arranged upon the reel that when it is pulled downwardly the roller will be turned in a direction to wind up the shade.

A bracket 7 is secured to the window casement adjacent to the end of the roller, and this bracket has an outwardly extending arm, provided with a downwardly inclined portion 8. The bracket arm has an arc shaped slot 9 which receives the trunnion 10 of the roller, and permits this trunnion to swing to an arc of approximately ninety degrees. The trunnion is journaled in an opening in a lever 11 which is pivoted to the

bracket, indicated at 12, eccentric to the trunnion 10.

This arm has a stirrup 13 at its free end through which the cord 6 is passed, and a roller 14 is journaled in the stirrup to prevent disengagement of the cord. When the parts are in normal position the roller occupies the dotted line position of Fig. 1, and in such position the axis of the roller will be horizontal. The weight of the roller and reel will cause the trunnion 10 to swing to the lower end of the slot 9, carrying the arm 11 into the dotted line position of Fig. 1.

When the roller is in such position the outermost flange of the reel will drop into a stirrup 15 at the end of the inclined portion 8 of the bracket 7, and the turning movement of the reel and roller will be braked by the engagement with opposite sides of the stirrup, as shown in Fig. 2. When the cord is drawn downward the parts swing into the full line position of Fig. 1, the arm 11 swinging forwardly and upwardly and carrying with it the reel and adjacent end of the shade roller, moving to the upper end of the slot 9. This upward movement of the reel disengages the flange from the brake shoe 15 and leaves the reel and roller free to rotate.

If it is desired to raise the shade the cord is drawn downwardly, and the shade will be wound upon the roller. If it is desired to lower the shade the cord is permitted to slip through the fingers, the weight of the shade being sufficient to cause the roller to turn in a direction to unwind the shade and to wind up the cord. When the shade is properly adjusted, the cord is released and the weight of the shade and roller will move the reel to cause it to engage with the brake shoe 15.

There is no necessity for touching the shade either in raising or lowering, it only being necessary to engage the cord. A steady continuous pull on the cord will raise the shade and a slight continuous release of the cord will lower the shade. A quick and total release of the cord locks the shade in adjusted position. When the cord is quickly released, the shade, especially if heavy, does not come to a sudden stop, which would probably injure the fabric or fixtures, but it is slowed down progressively to a stop with about one-half inch of movement. The action is due to the fric-

tional brake. When in the lower position about one-half of the weight of the shade and roller is forcing the flange of the reel into the brake shoe and any amount of pulling on the shade only serves to lock it tighter. There is no wear on the shade and the only wear in the entire device is on the pintles or trunnion.

In Fig. 1 the natural friction between the arms of the stirrup and the reel flange is relied upon to do the necessary braking. In Fig. 3 a plug 16 of cork or the like is inserted in the end of the bracket 17, it being held in place by a pin 18 which is releasable to permit the plug to be changed. This bracket 17 corresponds to the bracket 7 of Fig. 1.

In Fig. 5 the bracket 19 corresponding to the bracket 7 of Fig. 1 has an inclined groove 20 in which is mounted a ball 21. The flange of the reel engages between the ball and the opposite face of the stirrup, and it will be obvious that when the ball is moved into the shallow part of the groove, the bottom of the groove being inclined, the said flange will be tightly gripped between the wall and ball.

In Figs. 7 and 8 the bracket 22 corresponding to the bracket 7 of Fig. 1 may have a ball of rubber, cork or the like held in coöperating recesses 23 in the arms of the stirrup, the edge of the flange engaging the ball.

I claim:

1. A shade fixture having rollers comprising a reel secured to one end of the roller, a bracket on which the said end of the roller is supported, a lever pivoted to the bracket and having an opening for receiving the trunnion of the roller, the bracket having an arc shaped slot in which the trunnion is movable for permitting the roller to swing downward with respect to the bracket and to be moved upward by the swinging of the lever, the bracket having a brake shoe for engagement by the reel when it swings downward to prevent rotation of the roller and reel, and a cord winding at one end of the reel and slidably connected with the lever to swing said lever

and the trunnion upwardly to release the reel from the brake shoe.

2. In combination with a shade roller having at one end a reel and a trunnion at the axis of the reel, a fixed bracket for the trunnion, a lever pivoted to the bracket, the trunnion being journaled in the bracket eccentric to its pivotal connection, said bracket having a brake shoe for engaging the reel to prevent rotation of the roller when the reel is in lowermost position, a cord winding on the reel and slidably engaging the lever to swing said lever upwardly when the same is drawn downwardly to lift the reel out of contact with the brake shoe.

3. A shade roller having at one end a reel, a lever adapted to be pivoted to the casing and having a bearing for the reel, said lever being mounted to swing to move the reel and roller upwardly and downwardly, a brake shoe for engagement by the reel when it is in lowermost position to prevent rotation thereof, and a cord winding on the reel and slidably engaging the lever to permit the lever to be swung upwardly by the cord, said lever swinging downwardly under the weight of the reel and roller to cause the reel to engage the brake shoe.

4. A shade roller having a reel and a cord winding on the reel at one end, a lever adapted to be pivoted adjacent to the reel to a fixed support and supporting that end of the roller for rotation, the cord being connected with the lever to swing the roller upward, the weight of the roller swinging the lever downward, and a brake held in position to be engaged by the roller when it swings downward.

5. A shade roller having a cord winding thereon, a lever adapted to be pivoted adjacent to the reel to a fixed support and supporting that end of the roller for rotation, the cord being connected with the lever to swing the roller upward, the weight of the roller swinging the lever downward, and a brake controlled by the downward swinging of the roller.

WILLIAM McCORMICK NEALE.
